UNITED STATES PATENT OFFICE.

WILLIAM J. MCELROY, OF PITTSBURG, PENNSYLVANIA.

ELECTRIC SWITCH-BOARD.

SPECIFICATION forming part of Letters Patent No. 278,353, dated May 29, 1883.

Application filed February 5, 1883. (No model.)

To all whom it may concern:

Be it known that I, WILLIAM J. MCELROY, of Pittsburgh, county of Allegheny, State of Pennsylvania, have invented or discovered a new and useful Improvement in Switch-Boards; and I do hereby declare the following to be a full, clear, concise, and exact description thereof, reference being had to the accompanying drawings, making a part of this specification, in which—like letters indicating like parts—

Figure 1, Sheet 1, is a view in elevation of my improved switch-board. Figs. 2, 3, and 4 are views in elevation, to an enlarged scale, of plugs adapted for use in making switch or circuit connection on the board. Figs. 5 and 6, Sheet 2, are views in side and edge elevation of the induction-screen employed in the board. Fig. 7 is an edge view, partly broken away, of the switch-board; and Fig. 8 is a plan view of one corner of the board, a portion of the plates constituting the frame being broken away.

My invention relates to certain improvements in switch-boards; and, in general terms, it consists of certain combinations of an open frame, of conducting-bars secured by their ends across the central opening in the frame, and metal induction-plates between and separate from the bars, with means for securing the plates and bars and for making connection between different bars, as hereinafter more fully described and claimed.

In the use of switch-boards as ordinarily constructed, interference arises or exists to a considerable degree from two different sources—namely, conduction, sometimes called "leakage" or "escape," from one conductor to another through the body or substance of the board, and induction, due to the presence of one conductor within the field or lines of force of another electrically excited. The interference due to these causes is especially troublesome in telephone service owing to exceeding sensitiveness of these instruments to electric impulse.

The purpose of my invention is to provide a switch-board so constructed as to be free or practically free from disturbance due to these causes, thereby adapting it especially for use on telephone-lines, though it may be used with equally good results for ordinary telegraphic purposes.

In the drawings I have represented an open

rectangular frame, A, the bars or sides of which are made up of three layers of plates, a a' a'' , fastened together by screws a^3 in any desired number, whereby the parts or plates of the frame may be separated and replaced at pleasure. The bars of the frame may be secured together at the angles by lap-joints, or by tenon and mortise, or in any other convenient way. The material of the frame is by preference hard rubber or vulcanite, though other material which is a non-conductor of electricity may be employed.

The conducting-bars c e are passed across the frame from side to side, one set, e , being horizontal, and the other set, c , being vertical. The bars of each set are separated from each other a sufficient space to permit of the insertion between them of a plug, R, or S, (shown in Figs. 2, 3, and 4, enlarged or full size,) and also the separate sets of bars are separated in depth sufficient to prevent conduction of electricity from bar to bar through atmosphere under usual conditions of moisture and pressure. This separation in depth I have shown about equal to one-third the full thickness of the frame—say the full thickness of the middle plate, a' . (See Fig. 7.) In securing the bars to the frame their ends are passed into its sides, say, one-half their width (more or less) or sufficiently to give a firm support. (See Figs. 7 and 8, also dotted lines, Fig. 1.) In doing this recesses i , of proper size and form to receive the ends of the front or vertical bars, c , are made in the inner face of the front or face plate, a , (see Fig. 7,) and similar recesses, i' , are made for the ends of the horizontal bars e in the inner face of the back plate, a'' . (See Fig. 8.) In order to make electrical connection with the bars, one end is looped, as at c' e' , forming eyes, through which are passed the fastening bolts or screws n of binding-posts N, and to secure certain metallic contact the barrel n' of these posts is let into the plates of the frame, (see Fig. 7,) so that the inner shoulder, n^3 , presses firmly upon the side face of the eye. Instead of screw-bolts n , equivalent wood-screws or gimlet-pointed screws may be formed on the end of the barrel and screwed into the plate or plates below the eye. I prefer the bolts, however, as affording greater security and assistance in holding the plates of the frame together. The bars may be either rect-

angular in section, as represented in Fig. 1, or round, as in Figs. 7 and 8. I prefer the former on account of affording increased surface-contact with the switch-plugs presently described. 5 They are, by preference, made of steel or other good electric conducting metal or alloy capable of being hardened by tempering, so as to possess elasticity or spring action sufficient to prevent permanent bending or distortion of the bars. 10 Bars of soft or untempered metal may be used, however, if made of sufficient size or area in section to retain a straight form under the conditions of use. In this construction of the frame and bars there is no solid connecting substance between the bars of any kind, except at their ends, air only being in contact with them over the greater part of their surface. 15 Consequently conduction between wires will be limited to such end contact and be reduced practically to minimum or nothing. In this respect decided advantage is gained over boards employing a body or back in contact with the whole or greater part of the length of the switch-bars, as commonly practiced. It is 20 well known that air is among the best of insulators, and by providing for air-contact along with the whole surface of the bars, except their ends, I secure to a corresponding extent the greatest attainable degree of insulation, and 25 consequent protection against conduction or escape of electric force from wire to wire. In order to make the desired electric connection between the bars of the two sets, I make use of a plug, R, Fig. 2, having a head, r , of hard 30 rubber or other suitable non-conductor, and a four-pronged metal body, r' , the space r^2 between prongs corresponding in width to the thickness of the bars, so that the prongs may straddle the bars at the crossing-points, with 35 their flat inner faces pressing closely upon the flat side faces of the bars. Other than flat faces may be used, either on the bars or prongs, or both, and still secure electrical contact or connection. I prefer the flat forms, however, 40 on account of the increased contact-surface secured thereby.

In Figs. 3 and 4 I have shown a modified form of plug, S, more especially adapted to straddle around bars, as in Figs 7 and 8, consisting of non-conducting head s , short and long prongs $s' s^2$, forming a hook for engaging a portion of the surface of the front bar, the longer prong, s^2 , being split, as at s^3 , and having a seat or recess, s^4 , in such split, at or 55 near the point adapted to receive the rear bar, the two parts of the split prong separating to receive the bar, and then pressing it with spring action to insure good contact. In this form of plug the distance between the seats 60 should correspond accurately with the distance between bars, so as to press them firmly. This calls for accuracy of fitting, and for this reason, as well as for its adaptation to the preferred form of bars, Fig. 1, I prefer the form 65 of plug shown in Fig. 2. Both, however, embrace substantially the same features of four-

pronged construction, the short and long prongs $s' s^2$ forming two for the front bar, and the split in prong s^2 forming, in effect, two prongs for the rear bar. I therefore consider both these forms as coming within my invention, in the sense of being four-pronged, and thereby obtain the requisite support and impart the desired pressure-contact.

In providing against conduction of electric force in the construction of the board, as above described, one material and important source of interference is practically removed.

In order to provide against induction, two sets or series of plates or bars, $d b$, are employed, one set, as b , being arranged parallel with and midway between the front bars, c , or between pairs of such bars, and the other set, d , being arranged in like manner between the rear bars, e . These plates $b d$ are made of some soft conducting metal, by preference soft iron, and may be nickel-plated or otherwise coated to prevent oxidation. Also, if desired, the bars $c e$ may be protected in like manner.

As represented in Figs. 5 and 6, the plates $b d$ are arranged across each other, edge to edge, and they may be rigidly secured together in such relationship by screw-bolts or by soldering, or in other convenient way, forming what I term an "induction-screen," B, which is supported in position within the opening in the main frame A by corner-stays h on the back, secured by screws or in other convenient way. The combined width of bars $b d$ is, 100 by preference, about equal to the thickness of frame A, bringing their outer-edge faces and the side faces of the frame in or near the same planes. As before described, the two sets of bars $c e$ are let into the inner faces of the outer 105 pieces, $a a^2$, of the frame. Consequently each set of such bars will be nearly in central plane of their respective sets of induction-plates $b d$, as represented in Fig. 7, so that the latter will extend in depth both in front and rear of the 110 plane of the conducting-bars. Thus the induction-plates, so far as they extend, intercept all lines of force between conducting-bars, and if made of appreciable body or thickness—say 115 about equal to the thickness of the conducting-bars—they will arrest the force exerted in such lines, thereby protecting or shielding the conducting-bars. Also, by making the induction-plates to overreach or exceed the conductors in depth, both forward and backward, they cover 120 or subtend a greater arc of radiation than the conductors, and will shield them not only from direct radial lines of force, but also from diffusion of force, the conductors lying, as it were, within a deep shadow in the field of force, which 125 shadow is formed or projected by the over-reaching induction-plates. By projecting the conductors in this manner induction will be so far reduced as to give no trouble and for all practical purposes to be absent. The ends of 130 the conductors alone are unprotected, and the exposure thus made is so small as to produce

no troublesome interference. If desired, the induction-plates may be carried closer to the inner edge of the frame than shown, or they may be passed into the frame, say, the full depth of the conducting-bars. I prefer, however, to stop them a little short of the frame, as shown, in order better to prevent conduction.

If desired, the induction-screen may have ground-connection of any suitable kind to carry off any electric currents that may be excited therein by reason of its position in the field of force of the electrically-excited conductors.

I have shown the bars *c e* in each set grouped in pairs, forming loops for incoming and outgoing lines, and the induction-plates *b d* placed between successive pairs instead of between individual successive bars. This form of board is designed more especially for way-offices. For a terminal office all the bars would be separated by such induction-plates, as each bar might form part of a separate line. In both cases the bars forming parts of separate lines are separated by intermediate induction-plates. The forces which cause the interferences above described are, relatively speaking, small but difficult to control, and capable of causing serious trouble, especially in telephonic service.

The features of improvement herein described by which such troubles are materially reduced or practically removed are, therefore, of great utility and advantage.

I claim herein as my invention—

1. In a switch-board, the combination of two sets of conducting-bars crossing the board in different planes and directions for line-connections, with induction-plates of metal interposed between the conducting-bars in each set, substantially as and for the purposes set forth.

2. In a switch-board, the combination of frame *A*, with open interior, two sets of conducting-bars, *c e*, crossing the open space within the frame in different planes and directions, and induction-plates *b d*, interposed between the conducting-bars in each set, the conductors and plates being unconnected within the frame by solid substance, substantially as set forth.

3. The combination of frame *A*, conducting-bars *c e*, crossing the open space in the frame in different planes and directions, and induction-plates *b d*, interposed between the conducting-bars, and overreaching the bars in depth, both in front and rear, substantially as and for the purposes set forth.

4. The induction-screen *B*, composed of metal plates *b d* in different planes, crossing each other edge to edge, in combination with conducting-bars *c e*, interposed between the plates in or near their central planes and surrounding frame *A*, substantially as set forth.

5. A switch-board having a frame with open inner space and conducting-bars crossing such open space in different planes and directions, in combination with a switch-plug having separate prongs adapted to straddle the conducting-bars and press their side faces, substantially as and for the purposes set forth.

6. A switch-plug having a non-conducting head and a four-pronged metallic body, substantially as and for the purposes set forth.

In testimony whereof I have hereunto set my hand.

WILLIAM J. McELROY.
